UNITED STATES PATENT OFFICE.

ALEXANDER MCLEAN NICOLSON, OF NEW YORK, N. Y.

AUXILIARY APPARATUS FOR STEERING VESSELS.

1,392,786.

Specification of Letters Patent.

Patented Oct. 4, 1921.

Application filed December 17, 1917. Serial No. 207,479.

To all whom it may concern:

Be it known that I, ALEXANDER MCLEAN NICOLSON, a subject of the King of Great Britain, residing at New York, in the county 5 of New York and the State of New York, have invented new and useful Improvements in Auxiliary Apparatus for Steering Vessels, of which the following is a full, clear, concise, and exact description.

10 This invention relates to auxiliary apparatus for steering vessels.

An object of this invention is to provide method and means for steering or turning vessels in the state of rest or motion, especially under circumstances in which the vessel is not readily responsive to the helm.

15 A further object is to provide steering apparatus that may be applied to the vessel to turn it through any angle in any desired 20 direction as quickly as desired.

A further object is to provide steering apparatus that may be internally applied to the vessel independently of any outside medium.

25 In accordance with this invention these objects are accomplished by storing up rotational energies of opposite senses in the plane in which the turning of the vessel is desired and in transforming the desired part 30 of the rotational energy into rotational energy of the vessel, so as to turn the vessel in the desired sense.

One way of accomplishing this is to store 35 up rotational energy in flywheels and to have one or more flywheels rotating in each sense that it may be found desirable to steer or turn the vessel. By providing for the flywheels, suitable brakes firmly attached to the structure of the vessel, a turning of the vessel in any sense may be obtained by braking 40 the flywheel which is rotating in that direction, since by so doing the flywheel would tend to impart its rotational energy to the vessel.

45 Applying this principle to a ship as an auxiliary steering means, flywheels would be suitably placed in the ship's hull and rotated in a horizontal plane, one or more wheels being rotated clockwise and one or 50 more being rotated counterclockwise and each being provided with braking means. If it should be found that it is desirable to employ the flywheels for steering only under certain conditions, while at other times relying on the ordinary rudder, then it would 55 be preferable that at the time the steering is accomplished by the rudder that the fly-

wheels should exert no action on the steering of the ship. This may be done by making the rotational energies in the two directions 60 equal and opposite. With such an equality the ship could be steered by the rudder the same as if the flywheels were absent. When however at any time additional steering means would be desired, the proper flywheel 65 could be braked until sufficient rotational energy had been imparted to the vessel to produce the desired turning. The brakes could then be released and the energy of the flywheel restored at leisure to its initial 70 value.

From the above description it is apparent that this invention has a very wide application. A vessel possessing steering mechanism according to this invention, may be 75 steered by it while the vessel is either at rest or in motion and may be turned as suddenly as desired through one hundred and eighty degrees or more if necessary. Such a vessel could be readily steered by 80 this auxiliary means while, for example, at rest at dock or while entering or leaving harbors. This auxiliary means would be also a safeguard against collision with obstacles, where the vessel was in a fog or 85 was maneuvering so as to avoid torpedoes or to point guns in warfare.

It is also evident that the application of this invention is not limited to ships, but may be applied to any type of a vessel, such 90 as an aeroplane, a submarine or other crafts or bodies that require steering mechanism. Since in the case of aeroplanes or submarines, steering means is desirable in both a horizontal and a vertical plane, flywheels 95 rotating both clockwise and counterclockwise would be required in each plane, so that the vessel could be steered either up or down or to the left or to the right by braking the flywheel which is rotating in the direction 100 it is desired to turn.

If the rotating bodies comprise flywheels, they should preferably be designed so as to store up large amounts of rotational energy. It is evident of course that the amount of 105 rotational energy stored up will depend upon the mass and the square of the velocity of the rotating bodies, but excessive velocities are, in general, objectionable, so that the velocity factor is limited to some degree. In general, however, it will be found that sufficient angular velocity may be maintained in a flywheel weighing even less than one per cent. of the total weight of the ship, 110

but this invention is in nowise limited to such values. It is to be understood that the rotational energy necessary to rotate a vessel in a given direction may be distributed between a plurality of rotating bodies located at various points in the vessel in order to avoid the concentration at one point of the great stresses that would attend the use of this invention in large vessels.

10 For the better understanding of the invention, reference is made to the following detailed description taken in connection with the accompanying drawings in which Figure 1 represents an embodiment of this invention illustrated in connection with a ship; Fig. 2 is an enlarged drawing of a portion of Fig. 1; Fig. 3 illustrates another form of this invention in connection with a submarine; Fig. 4 is a circuit diagram 15 which may be employed for the apparatus shown in Fig. 3; and Figs. 5 and 6 represent still other forms this invention may possess. Like reference characters represent like parts in the various drawings.

20 Referring particularly to Fig. 1, 7 is a ship having the ordinary steering means or rudder, 9, and propeller, 8, placed at the stern. In accordance with this invention auxiliary steering means is provided within 25 in the hull of the vessel and comprising a plurality of flywheels, 10 and 11, each of which being capable of being rotated in a plane vertical to the plane of the drawing, by some suitable means such as a motor, 14 and 14' respectively. The two flywheels have their axles 16 and 16' and their bearings mounted in casings 18, 18', that are supported by the beams 19 and 20 which may be parts of two decks or floorings of the ship. 30 The motors 14 and 14' are bolted to vertical supports 22. Means for braking the flywheels is supplied by a plurality of Westinghouse air brakes of the well known type, in which the pressure of the pivoted arms 24 and 24' against the flywheels is controlled 35 by the air pressure in the cylinders 25 and 25'. This will be described later more in detail.

40 A plurality of flywheels 12, shown by dotted lines, may be located in any desired portion of the ship in any desired number. In order to understand, however, the operation of this invention, it will be necessary to consider only two flywheels, 10 and 11, which 45 are shown in detail in Fig. 1, and which are shown in an enlarged view in plan in Fig. 2, where the flywheel shown may be either 10 or 11, although it has the reference character 10. As described above, the source of power 50 for rotating the flywheel is a motor 14, suitably fastened to the beam, 19, by the support, 37, and connected to the shafting of the flywheel by the belt 30. Means for braking the flywheel, whereby the rotational energy of 55 the wheel may be transformed into rota-

tional energy of the ship, is provided by the two Westinghouse air brakes 25, which may be of any type desired. Herein they are shown to be of the type in which the greater the air pressure supplied to the cylinder 25 through the pipe 39, the greater will be the braking action of the arm 24 on the flywheel. The braking arm 24 is shown pivoted at the point 32 and is connected to the piston head 34 by the piston rod 35. The arm 24 is normally kept out of contact with the wheel by the coiled spring 36 which is sufficient to overcome the pressure in the cylinder against the piston head 34 when no braking is desired.

60 The operation of this invention for steering the ship 7 may now be readily understood if we refer back to Fig. 1 and assume that the flywheels 10 and 11 are being rotated by their motors in opposite directions—say for example, that wheel 10 is being rotated clockwise and wheel 11, counterclockwise. It is preferable for ease of operation of this invention that the kinetic energies of the two flywheels should be equal and 65 opposite in sign, which would mean, if they are similar in form, diameter and mass, that their velocities should be equal and opposite. In such a condition the system comprising the flywheels 10 and 11 has zero influence 70 upon the ship since the action of one is neutralized by the other. If now, with the two flywheels in rapid motion, other means besides the rudder 9 is desired for steering the ship in a certain direction that would 75 correspond to a clockwise rotation of the ship, the effect may be accomplished by braking the flywheel 10, which is rotating clockwise, until a sufficient amount of the 80 rotational energy of the flywheel has been 85 transformed into rotational energy of the vessel to cause the amount of turning desired. The amount of energy taken away from the flywheel 10 may then be restored at 90 leisure until its rotational energy equals that 95 of the flywheel 11. In a similar manner if 100 a counterclockwise rotation of the ship is desired the wheel 11 should be braked.

105 It is evident that this method of steering the vessel may be accomplished by any desired number of pairs of wheels which may be situated in any desired part of the ship above, below or at the water line and that the turning of the ship in a desired direction 110 may be effected by employing one or more 115 or all of the various wheels that are rotating in that direction. The number employed, of course, will depend largely upon how quickly the turning is to be done, since the more 120 flywheels braked the quicker will be the 125 turning of the vessel. In the drawing a plurality of flywheels 12 is shown in dotted lines to represent the flywheels similar to 130 wheels 10 and 11 which by pairs may have equal and opposite rotational energies.

It is to be noted that by means of this invention, it would be possible to turn a ship completely around in substantially its own length, as this invention functions equally 5 as well when the ship is stationary as when it is in motion.

In Fig. 3 is shown how this invention may be applied to serve as a means for steering a submarine vessel 40, both in a vertical 10 plane as well as horizontally, by a plurality of flywheels 41, 42, 43, and 44 which are rotated respectively by motors 45, 46, 47 and 48, each of which is located on the same shafting as its flywheel. The shafting for 15 wheels 41 and 43 have supports 50, 50' which are suitably fastened to the flooring 52, while the axles of wheels 42 and 44 are supported by bearings in casings, 53. It is obvious that any desired number of pairs of flywheels 20 may be employed to perform the steering in the two planes. For the sake of simplicity only two pairs are shown in the drawing. For purpose of illustration we may assume 25 that flywheels 41 and 42 are rotating clockwise, while wheels 43 and 44 are rotating counterclockwise in their respective planes. If now it is desired to steer the submarine 30 in either a vertical or horizontal plane, that flywheel which is rotating in the direction the movement of the ship is desired should be braked an amount sufficient to give the ship the amount of rotational energy desired. If it is desired to rotate the submarine 35 to the left in a horizontal plane, wheel 44 which is rotating counterclockwise should be braked mechanically or otherwise. If rotation to the right is desired, wheel 42 should be braked. In the same manner if flywheel 40 43 is braked the submarine will be steered downward, while the braking of wheel 41 will turn the submarine upward.

In Fig. 4 is illustrated an electrical method by which the braking of such a system as that of Fig. 3 may be accomplished. 45 70 to 77 inclusive are shunt wound motors, each of which may be employed for rotating a flywheel in such a manner as motors 45-48 of Fig. 3 are shown to be employed. The pair, 70 and 74 for example, may be 50 employed to rotate flywheels in a clockwise direction and the pair 71 and 75 to rotate wheels counterclockwise in a horizontal plane, while each of the pair of motors 72 and 76 and of the pair 73 and 77 may be 55 used to rotate flywheels clockwise and counterclockwise respectively in a vertical plane. The motors which are shown to be of the shunt wound type may be of any other well known type desired. Coils 70' to 77' 60 inclusive are the field windings of the motors. 80 is a generator for supplying power to the motors and which may be the ordinary ship's generator. Power is supplied to the motor 70 by switch 83 and conductors 84 and 85, across which conductors the field

winding 70' is shunted. Motor 74 is supplied with power by conductors 86 and 87. The field winding 74' is shunted across conductors 86 and 87 through switch 89.

In a similar manner motor 71 is supplied 70 with power by switch 90 and conductors 91 and 92, while motor 75 is supplied through the conductors 93 and 94, its field winding being shunted across conductors 93 and 94 through switch 95. Similarly motor 72 is 75 supplied through switch 97, while motor 76 is supplied through the same switch, but has its field winding connected across conductors 98 and 99 through switch 100. Also motors 73 and 77 are supplied by switch 101, 80 the field winding of 77 being supplied by the additional switch 105.

Assuming now that it is desired to turn the submarine containing these motors in a clockwise direction in a horizontal plane, 85 then it would be necessary to brake those motors that are rotating flywheels in a clockwise direction in that plane, which, under the assumptions made above would be motors 70 and 74. One way this may be accomplished, and the way illustrated in Fig. 4, is to disconnect the two motors from their source of power and then to allow one to act as the generator for supplying current through the field winding of the other in 90 such a direction as to tend to rotate it opposite to its normal direction of rotation. In the case of motors 70 and 74 this may be accomplished by first opening switch 83 and then changing the position of switch 89 to 95 contact points 110 and 111, whereby the motor 70 acts as a generator for the motor 74 supplying current through its field winding 74' in the opposite direction to that in which it is normally supplied, thereby braking 100 105 both motors. In order that the braking may be done as slowly or as suddenly as desired, an adjustable resistance 113 is inserted in series with field winding 74' when the switch 89 is on points 110 and 111, so that 110 the value of the current through field winding 74' may be regulated from a very small value up to practically the full value of the current supplied by the motor-generator 70. When the maximum value of the resistance 115 113 is included in the circuit, then only a small amount of current flows through field winding 74', so that only a little braking action is accomplished, but decreasing the value of the resistance will increase the braking to the point where the desired amount of rotational energy is supplied to the submarine, whereupon switch 89 may be thrown off contact point 111 into its normal position and switch 83 closed so that the generator 120 80 may restore the rotational energies of the flywheels attached to the motors 70 and 74 to their normal values by employing the rudder.

In a similar manner if a clockwise turn- 130

ing of the ship is desired, motors 71 and 75 should be braked and this may be accomplished by opening switch 90 and moving switch 95 over to points 114 and 115. The 5 braking of the flywheels attached to the motors will therefore be inversely proportional to the value of the resistance 116. When the desired turning has been accomplished the switch 95 may be thrown back to its normal 10 position and the switch 90 closed again.

A clockwise turning of the submarine in a vertical plane can be done by braking motors 72 and 76 by employing switches 97 and 100 and the adjustable resistance 118 in 15 the manner described above, and a turning counterclockwise will occur if the motors 73 and 77 are braked in the same way.

It is to be understood that the above described method of performing this operation 20 of braking the motors of Fig. 3 is not the sole way this may be done, as it may be performed by any well known mechanical or electrical method.

From the above disclosure it is apparent 25 that this invention would also be very valuable as a means for steering air vessels, such as aeroplanes. In Fig. 5 is illustrated a form of this invention that is particularly adapted for use with aeroplanes, although 30 its use is in no wise limited thereto. 125 and 126 are two supports which may form part of the structural framework of an aeroplane. 127 is a circular frame supported by the supports 125 and 126 and capable of being 35 rotated by some suitable means such as a crank 130, about an axis through the points 131 and 132. Inside the framework 127 and rotating about an axle 135 which is supported at the points 137 and 138 are two flywheels, 139 and 140 which have motors 141 and 142 for driving them. The two wheels are not integral with one another or with the axle, but are capable of rotating in opposite directions driven by their respective 40 motors. Assume that wheel 139 is being rotated in a clockwise direction while wheel 140 is being rotated counterclockwise. If now it is desired to steer the aeroplane in any given plane, all that is necessary to be 45 done is to rotate the frame 127 until the plane of the wheels 139 and 140 is parallel to the plane in which the turning is desired to take place, whereupon the proper wheel may be braked in any suitable manner until 50 a sufficient amount of the kinetic energy of the flywheel has been transferred into rotational energy of the aeroplane. The braking may then be stopped and the original kinetic energy of the wheel may be restored 55 at leisure by its motor without in anywise affecting the steering of the vessel during such restoration provided recourse is had to the helm for compensation.

One way of accomplishing the braking 60 of the flywheels of Fig. 5 would be to brake

them mechanically as in Fig. 2 for example; or the braking may be done by shortcircuiting the motor through an adjustable resistance as is well known, although it is not limited to these methods, as still others may be employed. Each of the flywheels may be hollow as is shown in the cross-sectional view of wheel 140 which may contain any suitable fluid for increasing the weight of the wheel when desired, or of decreasing 75 its weight by allowing the fluid to escape through stopcock 146. The sides of the hollow chamber may include suitable vanes 148 for impeding the rotational momentum of the fluid. 80

Fig. 6 shows still another method of rotating and braking the flywheels, in which both processes are performed by steam turbines. 160 and 164 are a plurality of turbines for rotating the flywheels 161 and 165, respectively, either in a clockwise or a counterclockwise direction when sufficient pressure is applied to the turbines through the pipe 162. Mounted on top of the two turbines are two other turbines 167 and 168 which are also connected to the shafting of the flywheels 165 and 161 respectively and the blades of the two latter turbines are so positioned that when steam is passed through pipe 169, they tend to turn their respective flywheels in opposite directions to their rotation as produced by the pair 160 and 164. 90

It is apparent that a ship may be provided with any number of structures similar to 100 the one of Fig. 6, part of which may be rotating clockwise and part counterclockwise in any plane in which steering is desired. A ship possessing the structure of Fig. 6 may be steered thereby by positioning the plane of the flywheels in the plane in which steering is desired and then maintaining a normal amount of rotational energy in the flywheels by turbines such as turbines 167 and 168. When however it is 110 desired to steer the vessel, say in a clockwise direction, steam to the turbines rotating flywheels in a clockwise direction should be shut off and suitable braking applied. Thus if turbines 167 and 168, are rotating 115 flywheels in a clockwise direction, their steam supply should be cut off and steam applied to the turbines 160 and 164 which action would tend to rotate the flywheels 161 and 165 in a counterclockwise direction, 120 thereby retarding their motion and transferring their energy to rotational energy of the ship. When the desired turning has been accomplished the braking action may be stopped and the original velocities of 125 the flywheels restored at leisure by helm compensation.

It is to be understood that this invention is not limited to the specific embodiments above described, as it will be evident to one skilled 130

in the art, that various modifications may be made in the apparatus shown without departing in anywise from the spirit of this invention as defined in the appended 5 claims. It is to be further understood that the above modifications are not limited to the particular type of vessel with which they are shown.

It is to be understood that the word vessel as used in this specification and the appended claims is generic to any kind of a body or craft to which steering mechanism may be applied, such as boats, ships, aeroplanes, undersea boats, hydroplanes, and the 15 like.

Furthermore it is to be understood that this invention is not limited to auxiliary steering apparatus having bodies rotating in every direction in which steering is desired. For example if it is desired to have auxiliary steering apparatus for turning a vessel in two directions in a given plane, the steering may be accomplished by having stored rotational energy in only one of 25 these directions. Increasing the amount of the stored energy will turn the vessel in one of the directions, while decreasing the rotational energy by braking will turn the vessel in the opposite direction.

30 What is claimed is:

1. The combination with a vessel having a rudder, of means for steering said vessel during an emergency, said means comprising means for storing up rotational energy in a given direction, and means for changing the amount of said rotational energy when a change in direction is desired.

2. The combination with a vessel having a rudder, of means for steering said vessel during an emergency, said means comprising means for storing up rotational energy in a given direction, and means for transforming a portion of said energy into rotational energy of the vessel.

45 3. A vessel, means comprising a rudder for steering said vessel under ordinary conditions in a given plane, and means comprising flywheel rotating in opposite directions for steering said vessel in said plane during 50 an emergency.

4. The combination with a vessel of means for steering said vessel under ordinary conditions and means for steering said vessel when it is not readily responsive to said 55 first named means, said second named means comprising a plurality of flywheels, means for rotating said flywheels in opposite directions in the plane in which steering is desired, and means for transforming a portion 60 of the rotational energy of one of said flywheels into rotational energy of the vessel.

5. The combination with a vessel of means

for steering said vessel under ordinary conditions and means for steering said vessel 65 when it is not readily responsive to said first named means, said second means comprising a plurality of flywheels, means for rotating some of said flywheels in one direction in the plane in which steering is desired, means for rotating other of said flywheels in an opposite direction in said plane, the flywheels rotating in the same direction having a combined mass of the neighborhood of one per cent. of the mass 75 of the vessel, and means for braking one of said flywheels that is rotating in the direction that a turning of the vessel is desired.

6. The combination with a vessel of 80 means for steering said vessel under ordinary conditions, a plurality of flywheels, means for rotating some of said flywheels in a clockwise direction, means for rotating other of said flywheels in a counterclockwise 85 direction, said flywheels being normally rotated at such speeds that the kinetic energy developed in a clockwise direction is substantially equal to the kinetic energy developed in a counterclockwise direction 90 whereby the rotational energy of said flywheels will not interfere at ordinary times with the steering of the vessel by said first named means, and means for braking some of said flywheels when said vessel is not 95 readily responsive to said first named means whereby said vessel may be steered.

7. The combination with a vessel of means for controlling the direction of said vessel under ordinary conditions and means for 100 controlling the direction of said vessel when it is not readily responsive to said first named means, said second named means comprising a plurality of flywheels, means for rotating at least two of said flywheels 105 in opposite directions in the plane in which the direction of the vessel is to be controlled, and means for changing the rotational energy of one of said flywheels to make effective said second named controlling means.

8. The combination with a vessel of means for controlling the direction of said vessel under ordinary conditions and means for controlling the direction of said vessel in an emergency, said second named means 115 comprising means for storing up rotational energies of substantially equal amounts in opposite directions in the plane in which the controlling action is desired and means for suddenly decreasing the value of the 120 rotational energy stored in one direction.

In witness whereof I hereunto subscribe my name this 15' day of December, A. D. 1917.

ALEXANDER MCLEAN NICOLSON.
